CLAIM

The ornamental design for a front portion of an armored vehicle, as shown and described.

DESCRIPTION

FIG. 1 is left, front perspective view of a front portion of an armored vehicle of my new design;

FIG. 2 is a right side view thereof;

FIG. 3 is a left side thereof;

FIG. 4 is a front view thereof; and,

FIG. 5 is a top plan view thereof.

The portions of the depicted embodiment shown in broken lines form no part of the claimed design.
